UNITED STATES PATENT OFFICE.

CHARLES E. SMITH, OF SAGINAW, MICHIGAN.

BEAN-SEPARATING MACHINE.

1,110,014.

Specification of Letters Patent.

Patented Sept. 8, 1914.

Application filed October 23, 1913. Serial No. 796,857.

To all whom it may concern:

Be it known that I, CHARLES E. SMITH, a citizen of the United States, residing at Saginaw, in the county of Saginaw and State of Michigan, have invented certain new and useful Improvements in Bean-Separating Machines; and I do hereby declare the following to be a full, clear, and exact description of the invention, such as will enable others skilled in the art to which it appertains to make and use the same.

This invention relates to bean-separating machines.

The object of my invention is to provide a machine so constructed that the rapid separation of the various grades of beans may be attained.

The object of my invention is attained by progressively distributing beans over the upper laterally sloping surfaces of an adjustable inclined table and the laterally sloping upper surfaces of an adjustable auxiliary inclined table. The beans are distributed along the main inclined table by means of closely spaced scraper blades. The perfect shaped beans roll downwardly and over the sides of the main table, while the rough or misshaped grade of beans, clay and foreign substances are retained and distributed over an auxiliary inclined table, where they roll or slide downwardly over the side edges thereof. The badly split beans, clay and foreign substances, owing to their reluctance to roll or slide, are retained by the scraper-blades and delivered over the end of the inclined auxiliary table.

Further objects of the invention are to provide a simple, inexpensive, yet efficient machine for separating beans that consists in certain novel features of construction, arrangement and combination of parts, or the equivalents thereof, as hereinafter described and claimed.

Referring to the accompanying drawings forming a part of this specification wherein like characters of reference denote similar parts throughout the several views: Figure 1 is a plan view of a bean separating machine embodying my improvements. Fig. 2 is a sectional view taken on line 2—2 of Fig. 1. Fig. 3 is a detail showing in end elevation the front sprockets, chains, main table and a pair of scraper blades. Fig. 4 is a detail showing the hinge connection between the two inclined tables.

As clearly shown in the drawings, 1 design-

nates the supporting frame of my bean-separating machine. One or more main inclined tables 2 having laterally sloping upper surfaces 3 are suitably mounted at one end on the supporting frame. Each main table 2 is mounted at its front end upon a cross-bar 4 carried in vertically adjustable blocks 5, which blocks are carried in guides 6 and adjusted up or down by means of adjusting-screws 7. The main tables are adapted to set at an incline and the upper ends of the tables are adapted to move, thus changing the inclination of the tables when the adjusting screws 7 are turned.

A plurality of scraper-blades having a straight section 8 and the opposed diverging or diagonally disposed sides 9 extending therefrom are secured at their ends in suitably spaced relation, to drive chains 10, which chains are mounted over sprockets 11 suitably supported at each end of the machine. The sprockets are driven by any suitable means, as a belt over a stepped cone pulley, as shown in Fig. 1. The scraper blades have their lower edges 12 shaped to conform to the laterally sloping surfaces of the inclined tables. The diagonally disposed ends of the scraper-blades assist the rolling tendency of the perfect beans and utilize the reluctance of the poorest split beans and foreign substance to roll or slide by crowding them toward the center or high part of the tables and finally depositing them over the end of an auxiliary table.

Suitably hinged, at 13, to the lower end of the main table 2 is an auxiliary table 14 having the laterally sloping upper surfaces 15. The auxiliary table 14 may be inclined to any desirable degree of slant independent of the main table, by means of a cord 16, or its equivalent.

The auxiliary table 14 is an important feature of the invention and it saves a grade of imperfect shaped beans known as second grade, whereas, with prior machines of this type, this grade of beans has been delivered with the clay and wasted.

Suitably supported stationary hoppers 17 located at the upper end of the machine are each provided with a hinged bottom 18 having its free end engaging the top edges of the straight sections of the scraper-blades 8 as they travel downwardly over the main table, thereby automatically feeding beans from the hopper upon the main tables between the scraper blades. The feed is accom-

plished by the up-and-down movement that is imparted to the hinged bottom. The quantity of beans to be delivered to each space may be regulated by the slide 19 adjustably mounted on each hopper.

A suitable tray is arranged beneath the machine containing three compartments A, B and C, but their equivalents may be employed in the form of spouts or the like.

- 10 From the above description, it will be observed that I provide a machine for separating beans, whereby the perfectly shaped beans will roll down the laterally sloping upper surfaces of the main inclined table and drop over the side edges thereof into compartment A; and whereby the rough shaped beans, split beans and the clay and foreign substances will be moved by the scraper blades to the inclined auxiliary table.
- 15 The auxiliary tables being set at a greater incline than the main table, the roughly shaped and best grade of split beans will roll or slide down the laterally sloping upper surfaces of the auxiliary table and drop over the side edges thereof into compartment B, while the poorest, split and the foreign substances will be moved by the scraper blades and dropped over the end of the auxiliary table, owing to their reluctance to roll or 25 slide down the laterally sloping upper surfaces of the auxiliary table.
- 30 Having thus described my invention, what I claim and desire to secure by Letters Patent is:

35 1. A bean separating machine comprising a supporting frame, an adjustable longitudinally inclined table having a laterally inclined surface and movable scraper blades having a straight back and diagonally disposed sides disposed above said table, for the purpose set forth.

40 2. A bean separating machine comprising a supporting frame, a longitudinally inclined table having laterally sloping sides supported thereby, a vertical adjusting device located at one end of said table and winged scraper blades arranged in close spaced relation to form a conveyer disposed above said table and adapted to move downwardly along said table, for the purpose set forth.

3. In a bean separating machine, the combination with a suitable feeding device; of a longitudinally inclined table having laterally sloping upper surfaces, means for vertically adjusting the upper end of said table; a second longitudinally inclined table hingedly connected to said first-mentioned table and having laterally sloping upper surfaces and a bean scraping conveyer comprising spaced blades having a straight back and diagonally opposed side wings integral therewith adapted to move downwardly along the upper surfaces of said tables, for the purpose set forth.

4. The combination of a main inclined table having laterally sloping surfaces; an auxiliary table having laterally sloping surfaces hingedly connected to said main table; and a conveyer disposed above said tables and adapted to move downwardly thereon comprising drive chains and a plurality of closely spaced scraper blades having straight backs and diagonally disposed sides, the ends of said sides secured to said drive chain and the lower edges of said blade being shaped to conform to the laterally sloping surfaces of said table.

5. The combination of a main inclined table having laterally sloping surfaces, an adjusting screw for vertically adjusting the upper end of said main table to change the longitudinal inclination thereof; an auxiliary table having laterally sloping surfaces hingedly connected to said main inclined table, means for vertically adjusting the lower end of said auxiliary table for changing the longitudinal inclination thereof; and a conveyer disposed above said table and adapted to move downwardly thereon, comprising a plurality of closely spaced scraper blades having straight backs and diagonally disposed sides and having their lower edges shaped to conform to the laterally sloping surfaces of the said table, for the purpose set forth.

In testimony whereof, I affix my signature in presence of two witnesses.

CHARLES E. SMITH.
